TOY SUBMERSIBLE BOAT

Samuel F. Speers, North Attleboro, Mass., and David O. Pressler, Providence, R.I., assignors to Hassenfeld Bros., Inc., Pawtucket, R.I., a corporation of Rhode Island

Filed Mar. 2, 1966, Ser. No. 1,238

Term of patent 14 years

(Cl. D34—15)

FIG. 3

FIG. 4

FIG. 5

FIG. 1 is a side elevational view of a toy submersible boat showing our new design;

FIG. 2 is a top plan view thereof;

FIG. 3 is a front elevational view thereof on an enlarged scale;

FIG. 4 is a rear elevational view thereof on an enlarged scale; and

FIG. 5 is a bottom plan view thereof.

We claim:

The ornamental design for a toy submersible boat, substantially as shown.
